NAIL HOLDING TOOL

Filed Jan. 7, 1931

INVENTOR.

BY *Thomas A. Smith*
H.M. Plaisted,
ATTORNEY.

UNITED STATES PATENT OFFICE

THOMAS A. SMITH, OF OVERLAND, MISSOURI, ASSIGNOR TO HARRY J. HAGEN, OF ST. LOUIS, MISSOURI

NAIL HOLDING TOOL

Application filed January 7, 1931. Serial No. 507,140.

This invention relates to certain new and useful improvements in nail holding tools, the peculiarities of which will be hereinafter fully described and claimed.

5 The main objects of my invention are first, to provide a simple useful tool to hold short nails or like articles while starting them into concrete or other material; second, to provide for holding nails of different size of 10 head; third, to provide suitable bearing surface in such a tool for starting nails having fins or slight projections or a rounding surface on the head instead of the usual flat surface; fourth, to hold the nail firmly in 15 position without the aid of the operator's hand after inserting the nail in the tool, so it retains its position automatically; and other points herein described and claimed.

In the accompanying drawing in which 20 like reference numerals indicate corresponding parts.

Fig. 1 represents a plan view of a tool exemplifying my invention;

Fig. 2, an end view of the same;

25 Fig. 3, a partial vertical section on the central axis X of Fig. 1 and the balance in side view;

Fig. 4, a partial section of one end of the tool showing a concrete stub nail held in 30 starting position to drive through sheet metal into concrete; and

Fig. 5, a similar view showing a nail with a larger flat head for holding expanded metal latch to concrete.

35 To overcome the difficulty of holding short nails with the fingers while starting them, various devices have been employed. Such former devices, such as spring clips of various forms engaging the sides of the nails

40 usually require to be held by the hand to maintain engagement with the nail after its insertion in the holder, otherwise it is liable to be disengaged from the holder. Also other forms comprise a tubular holder with a

45 plunger mounted therein for hammer impact and are more or less complicated.

My nail holder provides a simple effective and very useful starting tool for short nails or other articles and is adapted to hold the 50 inserted nail by the under side of its head

firmly in a suitable recess in the end of a solid bar, and automatically retain the inserted nail in its proper axial position so it is not liable to be accidentally dislodged in handling the tool while starting the nail in 55 concrete or other material. Furthermore, my tool is adapted to nails of different size and shape of head as will be hereinafter more fully described.

Referring to the drawing, the numeral 1 60 designates a solid bar preferably of tool steel and cylindrical or other suitable shape adapted to be held in the hand of the user. Its outer end 2 is rounded or tapered for impact of a hammer in starting a nail, while its opposite 65 end is provided with a suitable full circular recess for reception of and enclosing a nail head. This recess is preferably multiple in diameter and depth to accommodate nails of corresponding size and thickness of head. 70 Thus the outer recess 3 is larger and shallower than the inner recess 4. The larger diameter is suited to the reception of a nail with a flat head 5 while the inner recess 4 is suited to a nail 6 with a smaller but thicker head, as 75 shown in Fig. 4.

On the outer surface of this bar is mounted a plate slide 7, preferably curved to correspond with and lie flat against said bar. A finger pull 8 for operating the slide is provided at the end or elsewhere, while the other end of the slide is bent over opposite the recessed end of the bar and forms a fork 9 having an opening of substantially the diameter of the nail, so that the fork will engage the 85 underside of the nail head when the slide is adjusted, and thus hold the nail firmly in the recess.

Fastening means for securing this slide to this bar preferably consist of a fastening 90 screw 10 passing through a slot 11 near the forked end, and into a threaded pocket 12 in the side of the bar as shown in Fig. 3.

Since the underside of the fastening screw 95 is flat as shown, and the slide is curved corresponding to the solid bar, the head of the fastening screw will frictionally engage the outside of the slide at the ends of the slot, and be out of contact with the slide at the sides of the slot as shown in Fig. 3. This fric- 100

- tional engagement of the fastening screw at the ends of the travel of the slide as indicated in Fig. 3, tends to hold the slide in its adjusted positions at both ends of its travel.
6. For further security in maintaining adjustment of the slide automatically, I provide a spring below the slide and frictionally engaging the underside of the slide. This spring is preferably a coil spring 14 mounted in a 10 pocket 15 in the side of the bar beyond the slot, and further insures maintaining the adjusted position of the slide at both ends of its travel. Thus when adjusted outward as indicated in Fig. 3, the nail can be readily inserted 15 in the corresponding recess for the head, the forked end will rigidly engage the underside of the nail head and hold it firmly in the axial line of the bar, without further pressure of the operator's hand upon the slide.
20. This reduces the liability of the inserted nail being accidentally dislodged while placing it in its driving position, and insures its desired entrance into the concrete or other material under the impact of the hammer of the 25 operator on the end 2.

Some nails have heads that are provided with fins or slight projections, or a conical or rounded surface, and I therefore form the inner recess 4 with a concave center surface 30 16 in the central axis of the bar, which provides for such projections and yet allows firm contact of the periphery of the recess with the outer periphery of the nail head. Thus a thick headed nail, Fig. 4, is held by the forked 35 end firmly in line with the central axis of the bar, and a flattened or curved head of larger diameter is similarly held by the outer and larger recess 3, as shown in Fig. 5.

In use, the tool and the nail inserted there- 40 in is applied to the sheet metal, or other article to be fastened, and started by hammer impact into concrete for half its length, for example. Then the slide is adjusted outward and the tool is freed from the nail, allowing 45 the operator to drive the nail home to its fastening position by direct impact of the nail without the further aid of the tool.

I do not limit myself to the exact construction shown, except as by the appended claims.

50. I claim:

1. A nail holding tool comprising a solid cylindrical bar adapted for hammer impact on one end and recessed for a nail head on the other end, a plate slide having a slot 55 mounted on the outside of the bar having one end bent at right angles and having a rigid forked end disposed at the nail engaging end of the slide opposite said recess, a fastening screw in said slot, and means to hold the slide 60 in its adjusted position, substantially as described.

2. A nail holding tool comprising a solid cylindrical bar adapted for hammer impact on one end and having a recess in the axis of 65 the bar for reception of an inserted nail head,

a plate slide mounted on said bar having a forked end opposite said recess, a fastening screw passing through said slot into the bar, the underside of the screw head being flat to bear on the slide at the ends of the slot and 70 clear the slide when intermediate of the ends of the slot, and a spring mounted below said slide and tending to increase frictional engagement in the movement of said slide as limited by said slot, substantially as de- 75 scribed.

3. A nail holding tool comprising a solid cylindrical bar adapted for hammer impact on one end having at the opposite end a recess in the axis of the bar for reception of a 80 nail head, and having transverse pockets adjacent to the recessed end in the top side of the bar, one pocket being threaded for a fastening screw, a plate slide having a finger pull and a forked end opposing said recess to engage the under side of a nail head and having a side slot, a fastening screw passing through said slot into the threaded pocket, and a coil spring mounted in the other pocket and making frictional engagement with the 85 underside of said slide, substantially as de- 90 scribed.

In testimony whereof I have affixed my signature.
